UNITED STATES PATENT OFFICE.

JÖRGEN JACOBSEN MÖLLER, OF KIEL, GERMANY.

TELEPHONE-CIRCUIT.

SPECIFICATION forming part of Letters Patent No. 637,884, dated November 28, 1899.

Application filed June 2, 1893. Serial No. 476,328. (No model.)

To all whom it may concern:

Be it known that I, JÖRGEN JACOBSEN MÖLLER, a subject of the German Emperor, residing at Kiel, in the Province of Schleswig-Holstein, in the Empire of Germany, have invented certain new and useful Improvements in Telephone-Circuits; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

My invention relates to improvements in telephone systems; and it has for its object the provision of means whereby the receivers remain in circuit during calling without loss of call-bell or battery current or any interference with the call-bell or battery circuit and at the same time enables the sender to ascertain if the receiver is busy, as will now be described, reference being had to the accompanying drawing, which shows a diagrammatic view of a telephone system embodying my invention.

The line-wire L is directly connected to the automatic switch or hand-phone-carrying lever A at the point 1, said lever having a hook at one end, on which is hung the receiver F², and the other end contacts with two points 3 and 5, alternately connecting the receivers and the bell W to line, and between these points is an insulated projection p', which contacts with the lever n and closes the primary microphone-circuit, which includes the battery B' or other source of electromotive force.

The receiver-circuit is connected at one end with the contact 3 and at the other to the fulcrum s³ of the call-lever f, which is normally in contact with the grounded point s² through wires k' i g.

The call-battery B, grounded by wires c i g, is connected to line by wire a, point s', and lever f. A lightning-arrester S is placed in parallel with the instrument. One or more receivers F² F' may be placed in the receiving-circuit.

To call, the person takes the receiver from its hook, the point p' acting on the lever n,

thereby closing the primary or microphone circuit n 2 m^X, battery B', wire m, microphone M, wire m', primary winding of the induction-coil J, wire m², point 4, and lever n, at the same time breaking the bell-circuit at 5 and connecting the receiver-circuit at 3 3^a to line. The call-lever f is now depressed, sending current from battery B, lever f, wire k², receivers F² F', secondary of the induction-coil, wire k, contacts 3 3^a, lever A, wire b', to line L and called station, where the line L enters through wire b' and fulcrum 1, sending current through lever A, contact 5, wire e, bell W, wire g, to ground. The sender, by placing the receivers to his ear, can hear a vibration of the diaphragms in the receivers, due to the intermittent current in the line caused by the make and break at the bell of the called station.

Should the receiver at the called station be off its hook, the current will be grounded without passing through the bell W. Current in this case enters the called station from the line L at 1, and via A 3^a 3 k J k², receivers, to s³, lever f s² k' i g, to ground. A steady current will flow in this case, because it will not pass through a circuit-breaker, (the bell,) and no sound will be heard at the sending-station.

Having thus described my invention, what I claim as new therein, and desire to secure by Letters Patent, is—

1. In a telephone system, the combination with the main line, of a signal branch permanently grounded, a hand-phone-carrying lever normally connecting the latter to the main line, a three-point switch normally grounded, a branch in parallel with the signal branch including a hand-phone, terminating at the three-point switch and adapted to be connected to line through said hand-phone-carrying lever, and a subbranch permanently grounded and adapted to be connected to line through said three-point switch branch containing the hand-phone and hand-phone-carrying lever, substantially as set forth.

2. In a telephone system, the combination with the main line, of a signal branch permanently grounded, a hand-phone-carrying lever normally connecting the latter to the main line, a three-point switch normally grounded, a branch in parallel with the signal

branch including a hand-phone and secondary coil of a local talking-circuit, terminating at the three-point switch and adapted to be connected to line through said hand-phone-carrying lever, a two-point switch mechanically operated by said hand-phone-carrying lever and closing a local circuit containing a battery, microphone and primary of the induction-coil, and a subbranch permanently 10 grounded and adapted to be connected to line through said three-point switch branch

containing the hand-phones, and the hand-phone-carrying lever, substantially as set forth.

In testimony that I claim the foregoing as 15 my invention I have signed my name, in presence of two witnesses, this 15th day of May, 1893.

JÖRGEN JACOBSEN MÖLLER.
